CLAIM

The ornamental design for a kidney shaped bottle carrier, as shown and described.

DESCRIPTION

FIG. 1 is a top left front perspective view of a kidney shaped bottle carrier showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines are for illustrative purposes only and form no part of the claimed design.
